UNITED STATES PATENT OFFICE.

EDWARD POSSON, OF CHICAGO, ILLINOIS.

CAR-DOOR.

1,116,728.

Specification of Letters Patent. Patented Nov. 10, 1914.

Application filed March 15, 1913. Serial No. 754,512.

To all whom it may concern:

Be it known that I, EDWARD POSSON, a citizen of the United States, residing at Chicago, in the county of Cook and State of Illinois, have invented certain new and useful Improvements in Car-Doors, of which the following is a specification.

The principal object of my invention is to provide a new and improved side door for 10 railway freight cars.

Another object of my invention is to provide an outside door for a railway freight car that will make a grain-tight closure.

Others objects of my invention relate to 15 various features and advantages, and all of these will be made apparent in the following specification and claims, taken in connection with the accompanying drawings.

In the drawings, I have illustrated one 20 specific embodiment of my invention, so that its nature and advantages may be clearly illustrated.

The invention is defined in the appended claims.

25 Referring to the drawings Figure 1 is a general side elevation. Fig. 2 is a horizontal section on an enlarged scale, taken on the line 2 of Fig. 1. Fig. 3 is a horizontal section on an enlarged scale, taken on the line 30 3 of Fig. 1. Fig. 4 is a side elevation of the car wall surrounding the door opening, certain elements adjacent the side and bottom edges being removed to show other parts more clearly. Fig. 5 is a perspective 35 view of a guide clip for one side of the door opening. Fig. 6 is a perspective view of a guide clip for the other side of the door opening.

Referring to the drawings, the side wall 40 25 of the freight car has the door opening 26 adapted to be closed by a door 27, which, in the construction shown, comprises upright and transverse wooden frame members inclosed by sheet metal plates, two of 45 which, 30 and 32, are on the outside, and two more of which, 31 and 33, are on the inside of said frame members. The parts of the door are held together by rivets or bolts through the plates and through the 50 intermediate frame members. The door is supported below by rollers adapted to run on a track of suitable construction to form a grain tight closure along the bottom edge of the door and above the door opening an 55 overhanging lip 58 spaced from the wall 25 is adapted to form a grain tight closure

along the upper edge of the door. The handles 80 and 86 are adapted for use in manipulating the door on its supporting track.

60 The above mentioned features constitute no part of the present invention and are shown and described merely as a basis for illustrating one form of my improved means for forming a guide closure along the front 65 and rear edges of the door.

70 The side post 60 of the door opening has the door jamb 50 and the iron strip 61 attached thereto by a bolt 64, thus forming a vertical channel to receive the edge of the door. The corresponding edge of the door has its metal plates bent in a little as indicated at 63. A series of clips 62 are attached to the post 60 as shown in Figs. 2 and 4. The door post 65 on the other side 75 of the door opening has a part of its outer face cut away, as indicated at 69, and a metal strip 66 is attached by means of the bolt 67 so as to form a channel 69. Inclined metal clips 68 are applied as shown in Figs. 2 and 4. The corresponding edge of the door has a metal strip 70 attached by the rivets 72 and spaced inwardly from the door by the strip 71 so that it will enter the channel 69.

80 It will be apparent that the clips 62 and 68 serve to crowd the door outwardly just at its final closure so as to make a grain tight closure between the side strips 61 and 69 and the corresponding parts of the door. 90 A grain tight closure is thus automatically formed when the door is closed, and it will be evident that after the car is filled with grain the weight of said grain will assist the clips in maintaining such closure.

95 While I have described a specific form which my invention may take, it will be understood that I do not wish to be limited thereto, except as defined by the appended claims.

100 I claim:

1. In combination, a wall having a door opening therethrough, vertical channels on the sides of the door opening, a lip on one side edge of the door, said channels being adapted to receive the corresponding side edge of the door and said lip respectively, and spaced clips to crowd the door and lip tightly against the outer walls of said channels when said door is closed.

110 2. In combination, a wall having a door opening therethrough with door posts at

the sides thereof, a door jamb attached to one post, a lip attached to said door jamb, said parts being disposed to leave a channel between the door post and the said lip, a door with its edge adapted to enter said channel, and inclined clips attached to the post within the channel so as to force the edge of the door against the said lip.

3. In combination, a wall having a door opening therethrough with door posts at the sides thereof, a door jamb attached to one post, a lip attached to said door jamb, a door with its edge adapted to enter the channel within said lip, a second lip attached to the other door post and projecting therefrom in the same direction as said first named lip and outwardly from said wall, said door having an oppositely directed lip attached to its inner edge and adapted to engage said second named lip when said door edge engages said first named lip, and spaced clips to crowd the door outwardly when the door is closed.

4. In combination, a wall having a door opening therethrough with door posts at the sides thereof, said door posts projecting outwardly from said wall, one of said posts having a portion thereof cut away on the side thereof away from said door opening, a lip attached to said door post and projecting therefrom adjacent said cut-away portion, inclined metal strips secured in said cut-away portion opposite said lip, said lip being so disposed that a channel is formed between said lip and said inclined metal strips, and a door having a metal strip secured thereto and spaced therefrom, said last-named metal strip being adapted to fit into said channel when the door is closed.

In testimony whereof, I have subscribed my name.

EDWARD POSSON.
